UNITED STATES PATENT OFFICE.

ROSCOE F. MORGAN, OF KIEFER, OKLAHOMA.

WRENCH MECHANISM.

1,324,405.

Specification of Letters Patent.

Patented Dec. 9, 1919.

Application filed August 8, 1919. Serial No. 316,263.

To all whom it may concern:

Be it known that I, Roscoe F. MORGAN, a citizen of the United States of America, and a resident of Kiefer, in the county of Creek, in the State of Oklahoma, have invented certain new and useful Improvements in Wrench Mechanisms, whereof the following is a specification.

This invention relates to a wrench mechanism especially adapted for tightening and securing the cylinders of internal combustion engines to their engine cases.

In certain types of gas engines the inner end of the engine cylinder is secured to internal flanges of the outer end of the engine case by means of nuts which engage the stud bolts of the engine cylinder projecting through holes in said flanges. Access is obtained for screwing up these nuts through a hand hole in the engine case. In this way it is impracticable to apply the power so as to properly tighten the parts, and, moreover, owing to the difficulty of operating through the hand hole, much time is wasted.

The objects of this invention are to shorten the time required for this wrenching operation, to secure a tight joint between the cylinder and cylinder case, and to facilitate the work.

Figure 1 of the accompanying drawings represents a longitudinal section of the cylinder end of an engine case of the type herein referred to and of a cylinder secured thereto and a side elevation of one embodiment of this wrench mechanism in operative relation for tightening said cylinder to said case.

Fig. 2 represents an end elevation of the outer end of the cylinder showing the parts of the wrenching means in connection therewith.

Fig. 3 represents a transverse section of the engine case on line 3—3 of Fig. 1 looking upward and showing the parts of the wrenching means operative at the inner end of the cylinder.

The same reference numbers indicate corresponding parts in the different figures.

In the preferred embodiment herein illustrated of this invention A represents a longitudinal section of the outer end of an engine case of a certain type of internal combustion engine and H an engine cylinder secured thereto. In engines of this type

the engine case has guide blocks b, and is provided at its connecting end with an annular extension c having an annular recess d, and an inward flange e to which the cylinder is secured. This flange is provided with bolt holes f through which project the stud bolts fixed in the body of the cylinder at the inner end thereof. This engine case has a hand hole g. The engine cylinder H is adapted to set against the outer face of the inward flange e of the engine case and is provided with the usual stud bolts i set in body of the cylinder and projecting through the bolt holes f of said flange. These stud bolts are provided with nuts l which are tightened against the inner face of the flange e in securing the engine cylinder to its case. The cylinder H is provided at its inner end with an intermediate head and at its outer end with the usual stud bolts m set in the body thereof.

A wrench shaft 10, preferably constructed of steel, is provided at its inner end with a square or other angular projection 11 and at its outer end with an angular projection 12. This shaft is provided with an adjustable collar 15 which has a set screw 16. This collar is preferably provided with reduced steps 17 and 18 of different diameters to adapt the shaft to a stuffing box of different size in cylinders where larger pistons are employed.

A wrench shaft support 20, preferably composed of mild steel, consists of a bar adapted to span the outer end of the cylinder. This bar is provided at its opposite ends with holes 21 and 22 adapted to engage diametrically opposite stud bolts m on said cylinder and it is provided centrally of its length with a hole 23 which serves as a bearing for the wrench shaft 10.

A wrench 30 for tightening the stud nuts i for securing the cylinder to the case consists of a thin straight offset arm preferably composed of vanadium steel drop forged and provided at one end with a wrench socket 31.

A driving crank 40, preferably a drop forging, is provided at one end with an angular socket 41 which engages the angular projection 11 at the inner end of the wrench shaft 10. This crank is provided at its outer end with a stud 42 preferably carrying a grooved antifriction roller 43, which, preferably composed of case hardened steel,

contacts with said wrench 30. A set screw 44, preferably composed of tempered steel fastens the driving crank to said shaft.

An actuating wrench 50, preferably a drop forging, is provided with an angular socket 51 which fits the angular projection 12 of the wrench shaft 10. This crank driven manually or otherwise operates this wrench mechanism.

10 In the use of this wrenching apparatus, I first measure the length of the stuffing box and then adjust and fasten by means of the said screw 16 the collar 15 on the wrench shaft 10 at a point which will permit said 15 collar to serve as a stop against the inner end of said stuffing box, with the end of said shaft in its full diameter flush or nearly so with the outer end of said stuffing box and the angular extension 11 projecting 20 beyond the said box. Then the shaft 10 is passed into the cylinder and its inner portion projected through the stuffing box *j*, the collar 15 engaging the outer end thereof. Then the shaft support 20 is placed on the 25 shaft 10 and secured to opposite stud bolts *m* at the outer end of the cylinder. Then the driving crank 40 is passed through the hand hole *g* and placed on the extension 11 at the inner end of said shaft and secured 30 thereto by the set screw 44. The hub of this driving crank engages the outer end of the stuffing box and in conjunction with the collar 15 prevents endwise movement of the shaft 10. The wrench 30 is passed 35 through the hand hole *g*, applied to one of the nuts to be tightened and adjusted in inclined position toward the left in engagement with the antifriction roller 43 of the crank 40, as shown in full lines in Fig. 2. 40 The actuating wrench 50 is then applied by its socket 51 to the outer angular extension 12 of the wrench shaft 10. Then the actuating wrench 50 is moved a half turn and the driving crank 40 is thereby swung to 45 ward the right carrying with it the wrench 30 and putting the parts in position indicated in dotted lines in Fig. 2. Then, if necessary to complete the tightening, the parts are readjusted to normal position for 50 the beginning of the wrench stroke and another turn given the nut; the operation being repeated as many times as necessary.

I have herein described the preferred embodiment of my invention but changes may 55 be made therein without a departure from the spirit or scope of the invention.

I claim as my invention:

1. A wrench mechanism comprising a wrench shaft, shaft supporting means 60 therefor, a wrench comprising an arm adapted to swing past the end of said shaft in a path substantially at right angles thereto and provided with a wrench socket at right angles to said arm, a crank disposed 65 at the work end of said shaft and operative

to impart a swing to said arm for actuating said wrench, and means for actuating said shaft.

2. A wrench mechanism comprising a wrench shaft, shaft supporting means therefor, a wrench comprising an arm adapted to swing past the end of said shaft in a path substantially at right angles thereto and provided with a wrench socket at right angles to said arm, a crank disposed at the 70 work end of said shaft and having a sliding engagement with said arm for actuating said wrench, and means for actuating said shaft.

3. A wrench mechanism comprising a shaft supporting means having upper and lower bearings, a wrench shaft supported in said bearings and provided with an adjustable collar engaging one of said bearings for determining the position of said shaft, a wrench comprising an arm adapted to swing past the end of said shaft in a path substantially at right angles thereto and provided with a wrench socket at right angles to said arm, a crank disposed at the 80 work end of said shaft and operative to impart a swing to said arm for actuating said wrench, and means for actuating said shaft.

4. A wrench mechanism comprising a shaft supporting means having upper and lower bearings, a wrench shaft supported in said bearings and provided with an adjustable stepped collar engaging one of said bearings for determining the position of 85 said shaft, a wrench comprising an arm adapted to swing past the end of said shaft in a path substantially at right angles thereto and provided with a wrench socket at right angles to said arm, a crank disposed at the 90 work end of said shaft and operative to impart a swing to said arm for actuating said wrench, and means for actuating said shaft.

5. A wrench mechanism for tightening to 95 its engine case an engine cylinder having an internal head disposed near said case, said head being provided with a stuffing box, said mechanism comprising a shaft support adapted to span the outer ends of 100 said cylinder and provided near its opposite ends with holes adapted to engage opposite stud bolts of said cylinder and with an intermediate shaft bearing, a wrench shaft adapted to turn in said stuffing box 105 and shaft bearing, a wrench comprising an arm adapted to swing past the end of said shaft in a path at substantially right angles thereto and provided with a wrench socket at right angles to said arm, a crank 110 disposed on the inner end of said shaft and having a sliding engagement with said arm for actuating said wrench, and means for actuating said shaft.

6. A wrench means for tightening to its 115

engine case an engine cylinder having an internal head disposed near said case and provided with a stuffing box, comprising a shaft support adapted to span the outer end of said cylinder and provided near its opposite ends with holes adapted to engage opposite stud bolts of said cylinder and with an intermediate shaft bearing, a wrench shaft adapted to turn in said stuffing box and bearing, a crank disposed on the inner 10 end of said shaft and adapted to engage the inner end of said stuffing box, a wrench adapted for engagement of said crank, a collar adjustable on said shaft and adapted to engage the outer end of said stuffing box, 15 and an actuating crank at the outer end of said shaft.

ROSCOE F. MORGAN.
